UNITED STATES PATENT OFFICE.

JEROME B. LOCKERBY, OF ITHACA, NEW YORK.

TROLLEY-WHEEL.

SPECIFICATION forming part of Letters Patent No. 714,589, dated November 25, 1902.

Application filed January 27, 1902. Serial No. 91,407. (No model.)

To all whom it may concern:

Be it known that I, JEROME B. LOCKERBY, a citizen of the United States, residing at Ithaca, in the county of Tompkins and State 5 of New York, have invented a new and useful Trolley-Wheel, of which the following is a specification.

My invention is an improvement in trolley-wheel supports, and relates to the trolley- 10 wheel of the "overhead" system.

The object of my invention is to provide a support for the wheel in which the latter may be allowed a lateral movement, so as to positively engage the wire at all times.

15 Another object of my invention is to provide the wheel-supporting frame with outwardly-flaring spring-actuated arms, so that the wheel may be easily guided to engage the wire and to so arrange the arms that no injury or inconvenience will be experienced from cross-wires; and with these objects in view my invention also consists in certain details of construction and novelties of combination, as will be fully described in the following specification and pointed out in the 20 claims, reference being had to the drawings, in which—

Figure 1 is a perspective view of a portion of a trolley-pole having my improvement applied. Fig. 2 is a side view of my improvement. Fig. 3 is a sectional view on about the line 3 3, Fig. 2. Fig. 4 is a detail front view illustrating the manner of locking the wheel-supporting frame in position, and Fig. 5 is a 25 detail section on the line 5 5 of Fig. 4.

In carrying out my invention I provide the end of the trolley-pole A with a bracket-arm B, that is formed with a downwardly-projecting member B', whose outer surface is con- 30 caved and whose lower end terminates in a tapered socket B², in which is adapted to fit and operate a conical-shaped stem C' of a trolley-wheel-supporting frame C, which consists of the said stem and the side plates C². 35 C², as clearly shown. The plates are provided with apertures, through which project the ends of a shaft D, upon which is mounted the trolley-wheel E. Upon the outer ends of the shaft is also mounted guide-arms F, that are 40 held in position upon the plate by brackets G, carried by the plate, and in order to positively hold the arms in a vertical position I

arrange springs H upon the plate, whose free ends rest against the said arms and normally hold them in an upright position. These 55 arms have their outer ends terminate in outwardly and rearwardly projecting portions F', that form a guide by which the wheel is easily returned against the wire, and by providing a limited movement for the arms they are 60 permitted to swing back when the trolley-wheel passes a cross-wire, and thus slip over the wire with but a very slight jar.

As before stated, the wheel-supporting frame rests in a socket in the bracket, so that 65 the plate and wheel may be allowed to turn to accommodate the angles of the trolley-wire—such as on curves, &c.—and in order that the movement of the wheel may be limited I provide the stem C' with a pin H', that 70 operates in a slot H², arranged in the hub of the bracket B, and limits the movement of the wheel, but allows enough so that the wheel may rest squarely against the wire at 75 all times. This movement also decreases the danger of the wheel slipping the wire on curves, which is a very common complaint in the wheels now generally used.

It will thus be seen that I employ an exceedingly simple construction by which the 80 life of the wheel is prolonged, the wheel prevented from jumping or slipping the wire, and in which much valuable time will be saved through the avoidance of stopping the car to replace the wire, as is now done. 85

Having thus fully described my invention, what I claim as new, and desire to secure by Letters Patent of the United States, is—

1. The combination of a trolley-pole having a bracket mounted upon the end thereof, a 90 frame carried by the bracket, an axle journaled in the frame and having a trolley-wheel mounted thereon, guide-arms mounted upon the ends of the axle and having their free ends terminating in outwardly and rearwardly extending portions, guide-brackets arranged upon the frame and through which the arms pass for limiting the movement of said arms, and a spring mounted upon the frame and adapted to engage the said arms, 95 substantially as shown and described.

2. The combination of a trolley-pole having a bracket mounted thereon, a downwardly-extending arm formed upon the bracket, a

frame carried by the said arm and movable laterally thereon, means for limiting the movement thereof, a shaft carrying a trolley-wheel, spring-actuated guide-arms held upon the shaft and having their ends terminating in rearwardly and outwardly flaring portions, substantially as shown and described.

3. The combination of a trolley-pole having a bracket mounted thereon, a downwardly-extending arm formed integral with the bracket and having its outer face concaved and its lower end terminating in a socket portion, a frame having a stem arranged to fit the said socket, the sides of the said frame being circular in shape, and a shaft carried by the frame and having a trolley-wheel mounted thereon, the said plates being of a greater diameter than the wheel.

4. The combination of a trolley-pole having a bracket arranged upon the end thereof, an arm projecting from the bracket, a tapering socket formed in the free end of the arm, a frame having a tapering stem to fit within the socket for the purpose of holding the frame to the arm, a trolley-wheel mounted in the frame, guide-arms carried by the frame, springs secured upon the sides of the frame and engaging the said arms, and brackets arranged upon the frame for limiting the movement of said arms, substantially as and for the purpose set forth.
